US00D897847S

(12) **United States Design Patent** (10) Patent No.: **US D897,847 S**
(45) Date of Patent: ** Oct. 6, 2020

(54) **PRODUCT TRAY**

(71) Applicant: **COMCAST CABLE
COMMUNICATIONS, LLC**,
Philadelphia, PA (US)

(72) Inventors: **Ellen Tave Glassman**, Closter, NJ
(US); **Michael Boylan**, Brooklyn, NY
(US)

(73) Assignee: **Comcast Cable Communications,
LLC**, Philadelphia, PA (US)

(**) Term: **15 Years**

(21) Appl. No.: **29/728,798**

(22) Filed: **Mar. 20, 2020**

Related U.S. Application Data

(62) Division of application No. 29/643,280, filed on Apr. 6, 2018, now Pat. No. Des. 885,913.

(57) **CLAIM**

The ornamental design for a product tray, as shown and described.

DESCRIPTION

FIG. 1 is a top perspective view of a product tray, showing our new design;

FIG. 2 is a bottom perspective view of the product tray of FIG. 1;

FIG. 3 is a top view of the product tray of FIG. 1;

FIG. 4 is a bottom view of the product tray of FIG. 1;

FIG. 5 is a front view of the product tray of FIG. 1;

FIG. 6 is a rear view of the product tray of FIG. 1;

FIG. 7 is a left side view of the product tray of FIG. 1; and,

FIG. 8 is a right side view of the product tray of FIG. 1.

1 Claim, 4 Drawing Sheets
